UNITED STATES PATENT OFFICE.

WENDELL L. CARLSON, OF JAMESTOWN, NEW YORK.

FUSE-PLUG.

1,310,175.

Specification of Letters Patent. Patented July 15, 1919.

Application filed March 8, 1918. Serial No. 221,116.

To all whom it may concern:

Be it known that I, WENDELL L. CARLSON, a citizen of the United States, residing at Jamestown, in the county of Chautauqua and State of New York, have invented certain new and useful Improvements in Fuse-Plugs, of which the following, taken in connection with the accompanying drawings, is a specification.

10 The invention relates to devices commonly known as fuse plugs for electrical circuits which are adapted to protect fuses while conducting a normal current but will burn or "blow out" when an abnormal current passes through the same, thus preventing damage to the devices in circuit; and the object of the present invention is to provide a simple two-part plug in which the fuse is visibly inclosed so that a "blow out" 15 is quickly discernible, the parts being so interlocked upon one another that they are retained in firm contact by the threaded metallic sleeve which forms one of the metal terminals of the plug; and the invention 20 consists in the novel features and combinations hereinafter set forth and claimed.

In the drawings, Figure 1 is a top plan view of the closed plug showing the fuse through the mica plate in the top; and Fig. 2 is a top plan view of the two parts separated from one another with the mica plate retained in one of said parts while the fuse is retained in the other. Fig. 3 is a plan view of the mica plate. Fig. 4 is a side elevation of the fuse plug showing the upper end of the fuse connection to the outer metallic sleeve and in dotted line the connection to the terminal at the inner end of the plug. Figs. 5 and 6 show sectional views of the 25 two parts of the porcelain fuse plug without the metallic band, said parts being separated from one another, Fig. 5 showing the mica plate in the groove of one part and Fig. 6 showing the groove in the opposite site L-shaped portion which retains the edge of the mica plate. Fig. 7 is a plan view of the inner end of the fuse plug showing the inner terminal. Fig. 8 is a detail view of the fuse and the inner terminal detached 30 from the porcelain plug showing the manner of attaching the inner terminal to the end of the fuse. Fig. 9 is an elevation of the threaded or spirally corrugated ring terminal which binds the two porcelain parts of the fuse plug.

Like characters of reference refer to corresponding parts in the several views.

The numeral 10 designates one portion or member and the numeral 11 the other portion or member of the porcelain plug which are united at the L-shaped joint 12 by the metallic spirally corrugated or threaded band 13 which forms one of the terminals of the plug, the outer surfaces of the parts 10 and 11 being threaded at 14 to fit the band 13.

The parts 10 and 11 are preferably made of porcelain and each has portions of the chamber or opening therein, that is, when the two parts 10 and 11 are united by the band 13 they form, as it were, a small porcelain receptacle having the groove 16 a spaced distance from the top around the inner walls of the chamber 15 to receive therein the mica plate 17 so that the interior of the chamber 15 is always visible through said mica plate 17. The part 10 preferably has the inner end portion 18 thereon. This is attained by the angular shaped cut which provides the extension 19 to one side beneath and the inner end of the part 11 so that the edge of the extension 19 is engaged by the band 13 when said band is turned onto the correspondingly threaded outer surface 14 of the parts 10 and 11.

85 The inner terminal consists of a metallic plug 20 in the shape of a capped pin with a split stem into which one end of the fuse 21 fits so that it may be quickly and easily inserted therein. The stem of the pin or plug 20 fits within the hole 24 in the inner end of the portion 10 so as to press the parts of the split stem of the pin 20 together upon the end of the fuse 21 so as to hold said fuse therein, or it may be soldered within 90 said split stem. The opposite end of the fuse 21 is enlarged so as to extend out through the hole 23 in the side of the porcelain part 10 so as to receive the upper edge of the metallic band 13 thereagainst. The 95 flattened end 22 may be turned either upward or downward and so engaged as to be firmly held within the hole 23 and formed so as to be brought into firm contact with the metallic band 13, or soldered thereto.

100 It is apparent that the holes 23 and 24 are both contained in the part 10 so that the fuse may be attached firmly therein while the two parts 10 and 11 are separated, after which said parts may be united without dis-

105

110

- turbance to the attached fuse 21. Thus in assembling the fuse plug, the fuse is first attached to the pin terminal 20 and passed up through the holes 23 and 24, the stem of the 5 pin 20 fitting firmly within the hole 24. The end 22 of the fuse 21 is securely attached in the hole 23, the part 11 is placed against the part 10 with the mica plate 17 in the groove 16 extending within the two parts and the 10 metallic band 13 is then screwed onto the periphery of the two parts 10 and 11 and firmly against the end 22 thereby holding the two parts of the plug firmly in contacting relation and locking the mica plate 17 15 within the groove 16 of the two parts and bringing the band terminal 13 into contact with the end 22 of the fuse 21. It is apparent that the fuse 21 is always visible through the firmly held mica plate 17.
- 20 I claim as new:—
1. A fuse plug comprising two portions having an L-shaped joint therebetween allowing sidewise separation, said portions shaped to form a chamber therewithin having a groove around its walls a spaced distance from the outer end thereof, a mica plate fitting within said groove to form a transparent closure for said chamber, the peripheries of said portions threaded, a 25 threaded band to fit over said portions and hold them in contacting relation, one of said portions having holes therein one through the inner end and the other through the side thereof a spaced distance from said inner 30 end hole, a metallic pin terminal received in said hole in the inner end, and a fuse connecting said metallic pin terminal to said threaded band through said chamber and hole in the side.
  - 40 2. A fuse plug comprising an L-shaped semi-circular portion and a second semi-circular portion fitting into said L-shaped portion to form a round plug therewith, said portions having a chamber therein and a threaded exterior, said L-shaped portion having a hole in the inner end and a second hole through the side thereof, a metallic terminal in said inner end hole having a split stem compressed by the walls of said 45 inner end hole, a metallic band terminal threaded to fit said threaded exterior of said portions to said second hole, a fuse having one end engaged in the split stem of said metallic terminal and the other end extending 50 out through said second hole to be engaged by said band terminal and thereby connect said terminals, said portions having a groove around the inner walls of said chamber above said second hole, and a mica

plate fitting in said groove to render visible 60 the interior of said chamber while closing the same.

3. A fuse plug composed of two complementary sections each having a hollow interior so as to conjointly provide a chamber, 65 one of the sections having an extension forming an end for the chamber and the other section having one end seating on said extension, a fuse in the chamber connected at one end to the extension and at its opposite 70 end to the side of said first named section, a transparent plate forming a closure for the other end of the chamber, and a sleeve threaded over said sections.

4. A fuse plug composed of two complementary sections each having a hollow interior so as to conjointly provide a chamber, a 75 fuse in the chamber connected at its ends to one of the sections, a transparent plate secured to the sections to form a closure for 80 the outer end of the chamber, and a sleeve threaded over the sections.

5. A fuse plug divided along a line extending axially of the plug to form two sections separable by relative lateral movement, 85 each section having a hollow interior so as to conjointly provide a chamber, a fuse in the chamber, a transparent plate forming a closure for the outer end of the chamber, a sleeve threaded over the sections to hold 90 same assembled, and means to secure the plate to the sections so as to allow the latter to be separated upon removal of the sleeve.

6. A fuse plug divided along a line extending axially of the plug to form two sections separable by relative lateral movement, 95 a threaded sleeve encircling the members for holding same against movement, each of the sections having a groove adjacent the top thereof, and a transparent plate having its 100 opposite portions fitting in the respective grooves of the sections.

7. A fuse plug composed of two complementary hollow sections each exteriorly threaded and having faces which meet in a 105 line extending longitudinally of the plug to conjointly form a chamber and to allow separation thereof by relative lateral movement, a fuse in the chamber, means to close the chamber ends, and a sleeve threaded over 110 said sections to normally hold same against lateral movement.

In testimony whereof I have affixed my signature in the presence of two witnesses.
